UNITED STATES PATENT OFFICE.

CHARLES H. RASMUSSEN, OF BROOKLYN, NEW YORK, ASSIGNOR TO FERDINAND GUTMANN & CO., OF BROOKLYN, NEW YORK, A CORPORATION OF NEW YORK.

BOTTLE SEAL.

Application filed July 20, 1925. Serial No. 44,868.

My invention relates to complete closures for containers, such as bottles or jars, in which a closure proper is applied to the container to hermetically seal it and protect the 5 contents against deterioration until the contents are to be used when it is removed. Associated therewith I use a slip or dust cap, preferably made of seamless, drawn metal which is secured to the closure proper until 10 the latter is to be removed, and which is thereafter used to close the container to maintain the contents in a clean and sanitary condition until they are used up. It is my object to produce a simple, cheap and sanitary 15 closure and cap, the closure member of which can be applied to containers by existing machinery and which does not necessarily require a specially finished bottle or jar in order that it may be used.

20 In the drawing I have shown embodiments of complete closure applied to a bottle. Fig. 1 is a side view, partly in section, of one form of my improved structure; Fig. 2 a like view of the structure of Fig. 1 with 25 the closure proper removed and the slip cap in place; Fig. 3 a bottom view of the slip cap; Fig. 4 a detail, sectional view of the slip cap and closure proper of Figs. 1, 2 and 3 interlocked on a bottle; Fig. 5 a like view 30 of the slip cap in position for removal from the permanent closure; Fig. 6 a sectional view of a modified closure proper and the slip cap associated therewith; and Fig. 7 a side view of the slip cap shown in Fig. 6.

35 In the form shown in Figs. 1, 2, 3, 4 and 5 the bottle or other container 1 has the regular crown finished lip 2. The closure proper is the regular cap composed of a metal shell 3, with a depending skirt provided 40 with a plurality of corrugations 4 and a sealing gasket 5 and is affixed to the lip of the bottle in the usual manner.

45 The slip cap is preferably made of drawn, seamless metal so that no crevices will exist to retain dust, dirt, dried bottle contents, etc., and has a top 6 and side walls 7 which are provided with inwardly extending projections 8. In the form shown in Figs. 1 to 5 these projections are so proportioned and located with respect to the corrugations on the skirt of the crown cap that they may pass between them and it may be provided with a rolled, lower edge 9 to prevent cutting of the fingers in handling.

In use the slip cap is pushed over the top 55 of the closed container with its inwardly extending projections sliding between outer corrugations of the closure and meshing with inner corrugations. When the slip cap has been fully seated, as shown in Fig. 5, it is 60 given a slight twist so that the upper ends of the inner projections will pass under the corrugations on the closure proper and secure the slip cap in place. The inwardly extending projections 8 should be so located on 65 the skirt or side wall of the slip cap that their upper ends will engage the bottom edge of the closure proper when the slip cap is in place thereon.

To open the container the slip cap is twisted 70 slightly and pulled off, exposing the closure proper. This is then removed in the usual manner after which the slip cap can be slipped on or off the container, protecting 75 the contents from contamination. The slip cap, being preferably seamless, can be easily cleaned and kept in sanitary condition.

In the modified form shown in Figs. 6 and 7 I have shown how a slip cap may be frictionally secured to a closure proper. The closure 80 proper 10, may have a smooth skirt 11 instead of the corrugated one of a crown cap, is spun over the lip of the bottle and the slip cap 12 has a series of inwardly extending 85 projections 13 so located and proportioned that they will frictionally engage the skirt of the closure proper and secure the slip cap to the closure proper. The slip cap is pulled off and the closure proper removed 90 after which the slip cap is used in the usual 90 manner.

I am aware that specially finished bottles have been made to which bottles both the permanent, or closure proper, and the slip cap have been secured but my invention contemplates the hermetic sealing of the container at the packing house with a closure proper and a slip cap which engages the closure proper instead of the container itself 95 so that it cannot come off in transit or on the dealers shelf. The user can remove the slip cap without the use of tools and after the closure proper is removed the slip cap can be used in the usual manner.

100 I claim:—

1. As a new article of manufacture, a slip cap for containers having in combination a top and depending side walls, said side walls

105

being provided with a plurality of inwardly extending projections in position to have their upper ends co-act with a container closure on a container, whereby the slip cap is secured to the closure and held against accidental displacement.

2. As a new article of manufacture, a container closure comprising a closure proper provided with a top and a skirt, the skirt of 10 which is adapted to engage a lip on a container, and a slip cap composed of a top and side walls, the side walls being provided with inwardly extending projections so located and proportioned that they will pass 15 over the skirt of the closure proper and en-

gage the same to prevent the accidental separation of the two.

3. As a new article of manufacture, a container closure comprising a crown cap provided with a corrugated skirt, and a slip cap 20 composed of a top and side walls, the side walls having inwardly extending projections therein and adapted to fit over the crown cap with the upper ends of the projections on the slip cap engaging the lower 25 ends of the corrugations on the crown skirt to prevent accidental separation of the two.

In testimony whereof I have affixed my signature.

CHARLES H. RASMUSSEN.
